UNITED STATES PATENT OFFICE

LEE B. GREEN, OF LAKewood, OHIO, ASSIGNOR TO THE BORDEN COMPANY, OF
WARREN, OHIO, A CORPORATION OF OHIO

WASHING MACHINE

Application filed March 2, 1928. Serial No. 258,522.

This invention relates to improvements in washing machines, and has reference particularly to means for facilitating the handling of clothes in the operation of wringing.

5 One of the objects of the invention is the elimination of the commonly employed swinging wringer, while retaining the advantages derived from the use of such a wringer.

10 Another object is the provision of a clothes tray or trays supported upon the machine in such manner as to be movable with respect to a fixed wringer, that is, so as to hold the clothes to be fed to the wringer or to receive 15 them as they come from the wringer.

Another object is the provision of means for draining water from clothes upon such a tray and so directing it that it will flow back into the washing machine or into a tub 20 or other container used in conjunction with the washing machine.

A further object is the provision of means which will permit the lifting of an entire batch of clothes out of the hot wash water 25 in the machine tub by means of a stick or the like onto a tray positioned to one side of the tub, which tray when loaded may be moved back into a position above the washing machine tub for convenience in feeding 30 the clothes to the wringer.

Other objects and features of novelty will appear as I proceed with the description of that embodiment of the invention which, for the purposes of the present application, I 35 have illustrated in the accompanying drawings, in which—

Fig. 1 is a vertical sectional view of a portion of a washing machine in which my invention is employed, the section being taken upon 40 a line extending diagonally across the machine from corner to corner.

Fig. 2 is a plan view of one of the tray frames shown in Fig. 1; and

Figs. 3 to 7 inclusive are more or less dia- 45 grammatic plan views illustrating various arrangements of the two trays.

In the drawing I have indicated at 10 a washing machine tub. The construction of this tub and the kind of washing apparatus 50 to be employed therewith may be varied as

desired. In the top of the tub I have shown a removable cover 11, which will ordinarily be in place during the washing operation to prevent splashing and to help retain the heat of the washing water.

Adjacent the tub 10, and preferably adjacent one corner of the tub, in case the latter is of more or less rectangular shape, I mount a tubular standard 12, this standard being firmly fixed in position by some suitable means, as for instance by a bracket 13 at the bottom of the standard and a bracket 14 attached to the tub 10 near the top thereof, a set screw 15 in the bracket 14 being employed to prevent rotation of the standard 12.

On the upper end of the standard 12 there is mounted a casing 16 in which is located suitable transmission gearing for starting, stopping and reversing the drive of the wringer rolls 17, a handle 18 above the casing serving to control the operation in the usual manner. A shaft 19 extending upwardly through the standard 12 transmits power from a motor (not shown) to the wringer drive mechanism in the casing 16. 70 The wringer frame 20 is rigidly supported from the casing 16 by a hollow arm 21, and the casing 16 with the wringer carried thereby is prevented from turning upon the standard 12 by a suitable means such as a set screw 22.

Between the casing 16 and the bracket 14 I mount two forged or cast collars 23 which are bored to produce an easy rotating fit upon the standard 12, and are equipped preferably, although not necessarily, with detent balls 24 backed by coil springs 25 that are retained and protected by threaded plugs 26. Four equally spaced sockets are formed in the outer surface of the standard 12 at the level of each of the balls 24, so that the collars 23 are releasably held in any one of four positions. On each collar 23 there are two bosses 27 that are drilled to receive the ends of tray supporting frames 28 and 28' which are preferably built of heavy hardened wire as illustrated in Fig. 2.

A sheet metal tray 29 is supported upon the upper tray frame 28, being dished in the middle to extend downwardly somewhat 100

into the space within the circular portion of the frame. The central part of the tray 29 is perforated as shown at 30 to permit water to drain out of the tray into a drain spout 31 that is circular at its inner end and provided with a flange 32 running in a circular track formed by an offset ring 33 which is attached to the underside of the tray. The spout 31 thus extends in a substantially radial direction outwardly to or beyond the periphery of the tray, and may be rotated upon the tray so as to change its radial position with respect to the tray. While the construction illustrated for enabling the operator to position the drain spout anywhere along the periphery of the tray is the one which is at present preferred, other arrangements may be employed without departing from the spirit of the invention.

20 In the lower frame 28' I mount a second tray 34 which may be of a form very similar to that of the tray 29 but which does not have drain openings or a drain spout. Both of the trays 29 and 34 may be lifted off their supporting frames 28 and 28', respectively, for cleaning.

25 In Figs. 3 to 7, inclusive, I have shown a washing machine located in front of one of a pair of stationary tubs 35 and 36. In these figures the principal parts of the machine are indicated by the same reference numerals as are used in the preceding figures but in Fig. 7 I have shown in addition a clothes basket 37.

30 When two trays are employed as herein shown, the machine may be arranged with respect to the rinsing and bluing tubs, as illustrated in Figs. 3 to 7 inclusive, although this is not the only feasible arrangement. 35 Assuming that the tub 35 contains rinsing water and the tub 36 bluing water, the trays are first arranged as shown in Fig. 3, it being noted that the spout 31 is positioned so as to direct water from the tray 29 back into the washing tub 10. The clothes from the wash water in tub 10 are now transferred into the tray 29, the arrow A indicating the direction of movement of the clothes. If the wash water is very hot a stick may be 40 employed for the purpose. Considerable water drains off the clothes naturally and finds its way back through the spout 31 into the tub 10. As soon as the entire batch of clothes is out of the tub 10 and on the tray 45 29, the next batch of dirty clothes is put into the machine, the cover 11 replaced, and the washing operation resumed. While this is taking place the clothes on the tray 29 have considerable opportunity to drain and cool and hence may be more easily handled than where they are taken out of the wash water and immediately fed to the wringer. Furthermore, some time is gained inasmuch as the wringing does not interrupt the operation of the washing apparatus.

Now the tray 29 is swung upon its support around into the position illustrated in Fig. 4, the spout 31 being maintained in a position where it can deliver water into the tub 10. The clothes on the tray 29 are then fed through the wringer 20 onto the tray 34. When the wringing is completed the clothes then on tray 34 are pushed off into the rinse water in tub 35, as indicated by the arrow B.

70 Each of the trays 29 and 34 is now swung approximately 90° in an anti-clockwise direction to the positions shown in Fig. 5, with the spout 31 positioned to empty into tub 35. The clothes are now lifted out of the rinse water and moved over onto the tray 29, as indicated by arrow C, the space in front of the tub 35 being free so that the operator may stand in such position that a minimum effort is required in lifting the wet heavy clothes.

75 The tray 29 is now swung around into the position of Fig. 6, the spout 31 being maintained in position to deliver water back into the rinsing tub 35. Again the clothes are lightened by their natural draining. The clothes are now fed by the operator from the tray 29 through the wringer 20 onto the tray 34. When this wringing operation is completed the clothes are pushed or lifted off the tray 34 into the bluing water in tub 36, as indicated by arrow D.

80 When the bluing has progressed sufficiently the tray 29 is swung around into position over the tray 34, as indicated in Fig. 7, 100 with the spout 31 directed over the tub 36. The wet clothes are then lifted out of the tub 36 onto the tray 29, after which they are fed through the wringer 20 into a basket 37 placed to receive them, although, obviously, the tray 34 may be employed to receive them 105 in the first instance, if that is preferred.

85 While I have shown and described two trays, I appreciate that the tray 34 may be omitted and very satisfactory results obtained by the use of the single tray 29 with its drain spout 31. Hence it is not my intention to limit the invention in this respect. The use of the ball detents 24 or equivalent means to releasably hold the trays in any one of four 110 principal positions is also a preferred but not an essential feature of the invention. Still other changes may be made from the disclosure herein without departing from the spirit of the invention, and hence it may be stated in general that the specific disclosure herein is intended primarily for purposes of illustration only and should not be construed as a limitation upon the scope of 115 the invention.

120 Having thus described my invention, what I claim is:

1. In a washing machine, a tub, and a shallow receptacle mounted to swing upon a verti- 125

- cal axis to assume positions above the tub and to one side of the tub.
2. In a washing machine, a tub, and a shallow receptacle mounted to swing upon a vertical axis to assume a position above the tub or along either of two sides of the tub.
3. In a washing machine, a tub, a tray mounted to swing upon a vertical axis to assume positions above the tub and to one side of the tub, and means for draining water from said tray outwardly in any one of a plurality of directions for each position of the tray.
4. In a washing machine, a tub, a tray mounted to swing upon a vertical axis to assume a position above the tub or along either of two sides of the tub, and means for draining water from said tray outwardly in any one of a plurality of directions for any given position of the tray.
5. In a washing machine, a tub, a vertical standard adjacent to said tub, a clothes wringer fixed upon said standard, and a tray mounted to swing upon said standard at a level between the tub and the wringer.
6. In a washing machine, a tub, a vertical standard adjacent to said tub, a clothes wringer fixed upon said standard, a tray mounted to swing upon said standard at a level between the tub and the wringer, and means for draining water from said tray outwardly in any one of a plurality of directions.
7. In a washing machine, a tub, and a pair of trays mounted to swing independently upon a vertical axis adjacent the tub.
8. In a washing machine, a tub, a pair of trays mounted to swing independently upon a vertical axis adjacent the tub, one of said trays being provided with means for draining water outwardly in any one of a plurality of directions.
9. In a washing machine, a tub, a vertical standard adjacent said tub, a wringer fixed upon said standard, and a pair of trays mounted to swing independently upon said standard between said tub and wringer.
10. In a washing machine, a tub, a wringer fixed in position above the level of the tub, and a tray mounted to swing upon a vertical axis at a level between the tub and the wringer.
11. In a washing machine, a tub, a wringer fixed in position above the level of the tub, and a pair of trays mounted to swing independently upon a vertical axis at heights below the wringer and above the tub.
12. In a washing machine, a tub, a wringer fixed in position above the level of the tub, a vertical tubular standard adjacent the tub adapted to enclose a driving element for said wringer, and a tray mounted to swing horizontally upon said standard at a level between the tub and the wringer.
13. In a washing machine, a tub, a wringer fixed in position above the level of the tub,
- a vertical tubular standard adjacent the tub adapted to enclose a driving element for said wringer, and a pair of trays mounted to swing independently upon said tubular casting at heights below the wringer and above the tub. 70
14. In a washing machine, a tub, a vertical standard adjacent said tub, a shallow receptacle mounted to swing upon said standard above the level of said tub, and cooperating means between said receptacle and standard for releasably holding the receptacle in any one of a plurality of adjusted positions. 75
15. In a washing machine, a tub, a pair of trays each of which is mounted to swing independently of the other upon a vertical axis adjacent the tub, and means for releasably holding each of said trays in any one of a plurality of positions about its axis. 80
16. In a washing machine, a tub, a vertical standard adjacent the tub, a shallow receptacle mounted upon said standard above the level of the tub and capable of swinging entirely around the standard, and means for releasably holding the receptacle in any one of a plurality of positions. 85
17. In a washing machine, a tub, a tray mounted to swing upon a vertical axis adjacent the tub, and a drain spout extending outwardly to the rim of said tray. 95
18. In a washing machine, a tub, a tray mounted to swing upon a vertical axis adjacent the tub, a drain spout extending outwardly to the rim of said tray, and means for permitting said spout to assume any one of a plurality of radial positions. 100
